UNITED STATES PATENT OFFICE.

LEWIS C. BAYLES, OF EASTON, PENNSYLVANIA, ASSIGNOR TO INGERSOLL-RAND COMPANY, OF NEW YORK, N. Y., A CORPORATION OF NEW JERSEY.

PERCUSSIVE TOOL.

1,134,718.

Specification of Letters Patent.

Patented Apr. 6, 1915.

Application filed February 3, 1912. Serial No. 675,288.

To all whom it may concern:

Be it known that I, LEWIS C. BAYLES, a citizen of the United States, and resident of Easton, in the county of Northampton and 5 State of Pennsylvania, have invented a new and useful Improvement in Percussive Tools, of which the following is a specification.

The object of this invention is to provide a 10 novel rotation device for percussive tools.

In the accompanying drawings, Figure 1 represents a percussive tool of the piston hammer type in longitudinal central section with my improved rotation device applied 15 thereto. Fig. 2 is a transverse section taken in the plane of the line A—A of Fig. 1, Fig. 3 is a transverse section taken in the plane of the line B—B of Fig. 1, and Fig. 4 is a diagrammatic view showing more clearly the 20 construction of the controlling valve, its chamber and the passages leading to the work piston chamber and rocking piston chamber.

The tool cylinder is denoted by 1, the front 25 head by 2, the back head by 3, the handle by 4, and the controlling valve chest by 5. The work piston 6 is fitted to reciprocate in its chamber 7 and is controlled in its movements by the valve 8. A plate 9 is interposed be- 30 tween the front head 2 and the cylinder 1. The back head 3 is herein shown as comprising three members interposed between the handle 4 and the cylinder 1. A fluid pressure operated rocking piston 10 is located in 35 the chamber 11 and the rocking movements of this piston 10 are controlled by the valve 8. A chuck 12 is rotatably mounted in the front head 2, which chuck is adapted to receive a shank of the tool steel 13, the rear 40 end of which steel is arranged in position to be struck by the hammer piston 6.

A rotary shaft 14 extends through the cylinder 1, into the front head 2, and back head 3, which shaft forms a driving connection 45 between the rotation piston 10 and the chuck 12. In the present instance, the front end of the shaft is provided with a pinion 15 which meshes with a gear 16 on the chuck 12. Means are provided for clutching the 50 rotation piston 10 and releasing it from the shaft 14, by providing the rear end of the

shaft with a ratchet 17 and the piston 10 with a spring-pressed pawl 18 coacting therewith. This pawl 18 is shown as comprising a plate having two stem guides 20, 55 21, upon which the springs 22, 23, act. The rear end of the shaft 14 extends into the bore 19 of the rocking rotation piston 10, so that the axes of the piston and shaft are co-incident.

The valve 8 herein shown is the well known double-winged type in which one wing controls the inlet passages 24, 25, leading to the opposite ends of the work piston chamber 7 and the passages 26, 27, leading 65 to the opposite sides of the rocking piston chamber 11, and the other wing controls the exhaust passages 28, 29, leading to the work piston chamber intermediate the inlet passages 24, 25.

It will be seen that a rotation device constructed and arranged as herein shown and described is very compact and may be readily assembled and disassembled.

While I have shown and described this rotation device in connection with a percussive tool of the piston hammer type, I do not intend to be limited to such a type of tool, but contemplate the use of my improved rotation device in connection with percussive 75 tools of any type.

By the term "rocking piston" is meant one which oscillates or moves back and forth in other than a straight line.

What I claim is:

1. In a percussive tool, a cylinder, its front and back heads, a chuck rotatably mounted in said front head, a shaft extending from said front to said back head, gearing between said chuck and the front end of 90 said shaft, an oscillating piston trunnioned on the rear end of said shaft, and having a driving wing projecting into said back head rearward of said cylinder and a pawl and ratchet connection between said piston and 95 said shaft.

2. In a percussive tool, a cylinder, its front and back heads, a chuck rotatably mounted in said front head, a shaft extending from said front to said back head, having its forward end geared to said chuck, a ratchet on the rear end of said shaft an 100

oscillating piston trunnioned axially of said shaft, having a driving wing projecting into said back head- rearward of said cylinder and a pawl in said wing engaging said 5 ratchet.

In testimony, that I claim the foregoing as my invention, I have signed my name in

presence of two witnesses, this first day of February 1912.

LEWIS C. BAYLES.
